HOT WATER HEATER SHELL

Filed Feb. 19, 1936

UNITED STATES PATENT OFFICE

2,059,371

HOT WATER HEATER SHELL

Richard R. Legg, Oklahoma City, Okla.

Application February 19, 1936, Serial No. 64,770

1 Claim. (Cl. 122—17)

The invention forming the subject matter of this application relates generally to hot water heater shells, and particularly to shells designed for use in regions where the water to be heated contains alkali or other mineral deposits.

It is well known in this art that the interior surfaces of boilers become furred after use by deposits on such surfaces from the water heated therein. It is also well known that such deposits decrease the heating efficiency of the boilers to such extent as to render them useless, unless the deposits, or scale, be removed at frequent intervals.

The main object of the invention is to provide a shell for domestic use, with its main parts so arranged as to be readily taken apart for cleaning purposes, and as readily reassembled.

Other objects of the invention will become apparent as the detailed description thereof proceeds.

20 In the drawing:

Figure 1 is a central vertical section through a domestic boiler embodying my invention; and

25 Figure 2 is a perspective view of a member forming the bottom of the boiler having a flue integrally connected thereto.

In the accompanying drawing the reference numeral 3 designates the cylindrical shell of a domestic boiler having a head 4 formed integral therewith. The head 4 is provided with the usual water inlet 5 and hot water outlet 6. The head 4 is also provided with a central aperture 7 adapted to receive slidably the upper end of the flue 8; and this flue 8 has a flange 9 suitably secured, as by welding, to the upper part thereof. The flange 9 is shaped to correspond to the shape of the inner surface of the head 4 and has suitably fixed thereto a series of bolts 10 adapted to extend through aperture 11 formed in the head 4.

40 Preferably, the shanks of the bolts 10 are permanently secured to the flange 9 as by welding or by tight friction fit in the apertures 12 formed in said flange 9 to receive them. The screw-threaded ends of the said bolts extend through apertures 11 and through registering apertures 13 formed in a washer 14 which is shaped to fit snugly around the upper end of the flue 8 and against the curved outer surface of the head 4.

50 It is not, of course, essential that the head 4 be made integral with the cylindrical part 3. Obviously, it may be made separate and secured suitably to the upper end of the part 3 by welding or in any other suitable manner. The shape 55 of the head may be varied indefinitely, and the

flange 9 and washer 14 would be correspondingly shaped.

When the flue 8 is secured in position on the head 4 it extends downwardly in the shell 3 and coaxial therewith, to connect with the bottom 5 15. The bottom 15 is apertured to receive the lower end of the flue 8, which is then welded or otherwise permanently fixed to the said bottom 15. Preferably, the bottom 15 is dome shaped as shown in the drawing. However, the outer 10 part thereof is shaped to form an annular flange 16 which is provided with apertures 17 adapted to receive the shanks of bolts 18.

The lower end of the shell 3 is shaped to form an outwardly directed annular flange 19 apertured to receive the shanks of the bolts 18 which pass through the aperture 17 in the bottom 15. A burner casing 20 of about the same diameter as the shell 3 is provided at its upper end with an outwardly directed flange 21, which is also 20 apertured to receive the shanks of the bolts 18. A suitable gasket 22 is apertured also to receive the bolts 18 and is intended to be positioned between the flanges 16 and 19 of the bottom 15 and shell 3, respectively. 25

It will be obvious from inspection of the drawing that when the bolts 10 are loosened from the head 4 and the bolts 18 are also withdrawn from the registering apertures in the flanges 16, 19 30 and 21, the flue and bottom can be removed from the shell 3 as a unit, and all scale or other deposits can be readily removed therefrom. The removal of the flue and bottom from the shell 3 also gives access to the interior of the shell for 35 cleaning purposes. It will be noted that all the bolts of this device are arranged on the outside of the heater and are therefore not harmfully affected by the heat of the boiler or the deposits in the water heated therein. Furthermore, these bolts and their nuts are readily accessible from the outside of the heater, so that it requires no tool but a wrench to effect the separation of the several parts of the heater. 40

45 It is to be understood that the invention is not to be considered as limited to the specific construction and arrangement described herein, since it is evident that many changes may be made without departing from the scope of the 50 invention as defined by the claim appended hereto. For example, machine screws adapted to engage screwthreaded apertures in the flange at the upper end of the flue, may be readily substituted for the bolts shown in the drawing. 55

What I claim is:

A hot water heater comprising a shell having a top provided with a central flue aperture and with bolt receiving apertures around said central flue aperture, said shell having its lower end shaped to provide an outwardly directed flange, a flue extending lengthwise within said shell and slidably through said flue aperture, a bottom for said shell permanently connected with the lower

end of said flue, means for detachably securing said bottom to the said outwardly directed flange, an annular flange fixed to said flue near the upper end thereof, bolts permanently fixed to said annular flange and having threaded shanks passing freely through the bolt receiving apertures in said top, and nuts adjustable on said shanks to secure the flue detachably to said top. 5
